UNITED STATES PATENT OFFICE.

PHILIP A. MYERS, OF ASHLAND, OHIO, ASSIGNOR TO F. E. MYERS & BRO.,
OF ASHLAND, OHIO.

FORCE-PUMP.

SPECIFICATION forming part of Letters Patent No. 691,654, dated January 21, 1902.

Application filed September 20, 1900. Serial No. 30,589. (No model.)

To all whom it may concern:

Be it known that I, PHILIP A. MYERS, a citizen of the United States, residing at Ashland, Ohio, have invented certain new and useful 5 Improvements in Force-Pumps, of which the following is a specification.

My invention relates to improvements in double-acting force-pumps; and the object of the invention is to simplify the construction 10 to a great degree and to increase the efficiency and durability and render the valves readily accessible.

I have illustrated the invention in the accompanying drawings, in which—

15 Figure 1 is a plan view of the pump with the cap removed. Fig. 2 is a similar view with the valve-diaphragm also removed. Fig. 3 is a cross-sectional view of the pump. Fig. 4 is a plan view of the cap, taken from the bottom. Fig. 5 is a longitudinal sectional view taken on the line xx , Fig. 1, and yy , Fig. 4. Fig. 6 is a longitudinal sectional view of the cap. Fig. 7 is a view similar to Fig. 1 of a modification, and Fig. 8 is a view of the cap used in 25 this form.

In the figures, A represents the body of the pump, which is preferably in the form or shape shown and made by casting in a single piece, it being provided with a suitable base 30 A', designed to be bolted to the floor or any other suitable support. The body A includes a horizontal cylinder, which is arranged low down upon or close to the base and contains a piston B of suitable construction. The 35 ends of the cylinder are closed by heads A² and A³, bolted to the body, and through one of the heads A² passes the piston-rod, which is preferably operated by a lever C, having its lower end connected by a link C' to a projection from the head A². An inlet-port D is located on one side of the cylinder, and an outlet-port E is similarly arranged upon the opposite side, these ports being formed by integral flanges projecting from the body of the 40 casting and adapted for feed and delivery pipe connections. The upper portion or side of the body A is made perfectly flat, as indicated at a, to receive the valve plate or disk I, (hereinafter more fully described,) 45 above which is mounted the cap F, secured in place by suitable bolts. From the inlet-

port D a passage d extends upward toward each end of the cylinder, terminating in a port d', which is normally closed by a weighted flap-valve i' and which opens automatically 55 upward on the suction-stroke of the piston to permit the water to pass from the inlet-port upward into the space or compartment between the cap and the valve. In close proximity to the port d' and valve i' is a port d², 60 leading down into the interior of the cylinder at each end, the valve plate or disk being cut away, as shown, to provide an opening corresponding to this port. The cap has a division web or rib f, which rests against the 65 valve-disk and divides the space above the same into three chambers f', f², and f³, the inlet ports and valves just described opening, respectively, into chambers f' and f². The third compartment f³ is in communication 70 by two ports or passages d³ with the opposite ends of the cylinder, flap-valves i², similar to those already described, closing these ports. This chamber also communicates by a port d⁴ with the outlet-port E of the body 75 and is also in communication with the air-chamber.

The arrangement being such as described, the operation of the pump will be clear, but may be briefly described as follows: Supposing the piston to be moving from right to left, the suction created behind the piston would cause valve i' to lift and the water to pass by ports or passages d' and d² to the space behind the piston. Simultaneously the water in front of the piston would be forced through the passages or ports d³ into the chamber or compartment f³ and thence through port or passage d⁴ to the delivery-port. 85

In the modified form the air-chamber is dispensed with, as is also the outlet-passage d⁴, and the outlet is directly from the top of the cap, as shown at d⁵, the action in other respects being substantially the same. 90

In order to drain the cylinder of any sediment which may accumulate therein, openings k are provided at the lower part of each end thereof, which are closed by screw-plugs. In the modified form the cut-away space in the valve-leather may be drained in a like 100 manner by a drain-opening l, closed by a suitable plug.

The valve-disk is simply a sheet of leather or the like cut to the shape shown, the valves formed by the circular tongues being weighted by suitable flat metal plates, as indicated.

5 By this form of valve-disk the valves are all assembled, so that by removing the cap they are all exposed to view, and they may be easily renewed when worn or damaged.

It will be understood that while I have 10 shown the valves as circular weighted tongues carried by a single valve disk or sheet and prefer this form, I may use any ordinary and well-known form of valve, if desired.

Having thus described my invention, what 15 I claim is—

1. In a force-pump, a single horizontally-disposed cylinder having a piston therein, said cylinder having a thickened upper wall with a flat face, a cap having integral webs 20 coacting with said flat face to form a double and two single valve-chambers, an inlet-port formed in the side of said cylinder and having branch ports leading to said single valve-chambers, valves controlling said ports, 25 passages in the body of the cylinder leading from said single chambers to opposite ends of the cylinder, ports in the body of the cylinder leading from the ends of the cylinder to the double chamber with valves controlling said 30 ports, and a water-outlet from said double chamber, substantially as described.

2. In a force-pump, a single horizontally-disposed cylinder having a piston therein, said cylinder having a flat upper face, a cap 35 having integral webs coacting with said flat upper face to form a double and two single

valve-chambers, branch ports in the body of said cylinder leading to said single valve-chambers, valves controlling said ports, an inlet-port for supplying water to said branch 40 ports, passages in the body of the cylinder leading from said single chambers to opposite ends of the cylinder, ports in the body of said cylinder leading from the ends of the cylinder to the double chamber, and a water-outlet from said double chamber, substantially 45 as described.

3. In a force-pump, a single horizontally-disposed cylinder having a piston therein, said cylinder having an upper wall with a flat 50 face, a cap having integral webs coacting with said flat face to form a double and two single valve-chambers, an inlet-port formed in said cylinder and having branch ports leading to said single valve-chambers, valves controlling 55 said ports, passages in the body of the cylinder leading from said single chambers to opposite ends of the cylinder, ports in the body of the cylinder leading from the ends of the cylinder to the double chamber with 60 valves controlling said ports, a compressed-air chamber carried by said cap having its interior in communication with said double chamber, and a water-outlet from said double chamber, substantially as described. 65

In testimony whereof I affix my signature in presence of two witnesses.

PHILIP A. MYERS.
